UNITED STATES PATENT OFFICE.

GEORGE K. FARRINGTON AND HOMER C. FARRINGTON, OF KIRKSVILLE, MISSOURI, ASSIGNEES OF ONE-THIRD TO BRADFORD S. POTTER, OF EDINBOROUGH, PENNSYLVANIA, SAID GEO. K. FARRINGTON ASSIGNEE TO H. C. FARRINGTON.

MECHANICAL TELEPHONE.

SPECIFICATION forming part of Letters Patent No. 271,324, dated January 30, 1883.

Application filed August 28, 1882. (No model.)

To all whom it may concern:

Be it known that we, GEORGE K. FARRINGTON and HOMER C. FARRINGTON, citizens of the United States of America, residing at Kirksville, in the county of Adair and State of Missouri, have invented certain new and useful Improvements in Mechanical Telephones, of which the following is a specification, reference being had therein to the accompanying drawings.

This invention relates to improvements in that class of telephones termed "mechanical," and is designed more especially as an improvement on the mechanical telephone invented by us, and for which United States Letters Patent No. 252,024 were granted to us on the 10th day of January, 1882.

The object of our present invention is to obviate the ringing or roaring sound and reverberation produced in telephones by the impact of sound upon the diaphragms, and thus secure a clear and distinct articulation of syllables and words, so necessary to have in a speaking-telephone.

A further object of our invention is to secure a firm and durable connection of the line-wire to the button of the diaphragm, and also secure a perfectly-equalized tension on each diaphragm in one instrument with each diaphragm in the other when the line between the two instruments is drawn, thus securing an equal or the same tension of line and diaphragms, so necessary to an accurate repetition of sound or tone from one instrument to the other.

The nature of our invention will be herein-after described more fully, and pointed out in the claims.

The accompanying two figures of the drawings represent a vertical section and a front elevation of the telephone, in which A is the case; B B', the diaphragms, attached to the diaphragm-frame C; and F, the rear wall of case, forming a sounding-board. The combination and arrangement of these elements—to wit, the case, the diaphragms, and the rear wall—form the air-chamber D between the diaphragms B B' and the air-chamber E in front of the rear wall, F, as seen in Fig. 1 of the drawings.

The letter G indicates a metallic tube, one

end of which is inserted in a chambered recess, n, in the sounding-board, F, the other end resting on a button, k'.

H is a metallic cap, to the inside of which is soldered or otherwise secured the ends of the line-wire i, (composed preferably of two strands of wire twisted together,) which passes through the cylindrical tube j, upon the outside of which tube is a screw-thread to retain the nut l. A washer, m, is also secured to the tube j, and arranged under metal cap H. This metal cap m also rests upon a button, k. The tube j and line i pass through the center of the diaphragms B B' and buttons k k'. When the diaphragms are tacked or otherwise secured on the frame C, the tube j and line i with button k are passed through them, and also through k'. The nut l is then screwed onto the tube j, and the diaphragms are drawn together, as shown in Fig. 1, in the shape of an hour-glass. The tube G having been put into the recess n in sounding-board F, the diaphragms are inserted into the case A, the button k' resting against the end of tube G. Now, when the line i is tightened (by means of pulleys or otherwise) between the instruments, the two diaphragms in each instrument are brought to the same degree of tension, the diaphragm B being pressed inward by being drawn against tube G, and the diaphragm B' being drawn inward also by the same tension of the line on the cap H and button k, thus equalizing the tension on both diaphragms. The tube G also forms a rigid center or sounding-post between the diaphragms B B' and sounding-board F. This tube or sounding-post, being hollow, does not obstruct the sound-wave or vibration from one instrument to the other from first striking the diaphragms; but the sound, having first been impacted on the diaphragms, is instantaneously transmitted by the tube to the sounding-board, which resounds simultaneously with the diaphragms in the expansion and contraction of the air in the air-chambers D and E. The diaphragms being rendered rigid at the center by means of the buttons k k' and tube G, the vibrations of the surrounding parts of the diaphragms are concentrated to the center, shortened, and quickened, effectually preventing the ringing and roaring so detrimental to clear ar-

ticulation and ease in conversation. By this improvement a clear and sharp articulation is obtained, and conversation can be carried on without making pauses between syllables and 5 words, (to allow ringing to subside,) as has hitherto been the case in telephones of this class. This tube or sounding-post is applicable to all telephones using single or double diaphragms. It may be made of metal, wood, or other suitable material.

It will be observed that this organization and arrangement of parts makes a very simple and cheap instrument.

We reserve the right to change the construction and shape of the instrument without departing from the spirit of the invention.

Having thus described our invention, what we claim as new, and desire to secure by Letters Patent, is—

1. A mechanical telephone composed essen-

tially of the case A, the diaphragms B B', sounding-board F, tube G, and the air-chambers D and E, with connecting means substantially as described.

2. In a telephone, the tube or sounding-post 25 G or equivalent, in combination with a sounding-board, F, and a single or double diaphragm, substantially as described.

3. In a telephone, the tube or sound-post G, in combination with the cap H, buttons k k', 30 line i, screw-tube j, diaphragms B B', and sounding-board F, substantially as described.

In testimony whereof we affix our signatures in presence of two witnesses.

GEORGE K. FARRINGTON.
HOMER C. FARRINGTON.
